(57) **CLAIM**

The ornamental design for a vertical connection spring-cage
PCB terminal block, as shown and described.

DESCRIPTION

FIG. 1 is a top, front, and left side perspective view of the
vertical connection spring cage PCB terminal block, showing
my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a top plan view thereof;

FIG. 8 is a top, front, and left side perspective view of an
alternative embodiment of three of the vertical connection
spring-cage PCB terminal blocks in a stacked configuration;

FIG. 9 is a front elevational view thereof;

FIG. 10 is a right side elevational view thereof;

FIG. 11 is a left side elevational view thereof;

FIG. 12 is a rear elevational view thereof;

FIG. 13 is a bottom plan view thereof; and,

FIG. 14 is a top plan view thereof.

The broken line portion in the drawing views is included to
show unclaimed subject matter only and forms no part of the
claimed design.
